(57) **CLAIM**

The ornamental design for a joint for pipes in particular for flexible tubes, as shown and described.

DESCRIPTION

The patent or application file contains at least one drawing executed in color. Copies of this patent or patent application

publication with color drawing(s) will be provided by the Office upon request and payment of the necessary fee.

FIG. 1 is a top plan view of a first embodiment of a joint for pipes in particular for flexible tubes in accordance with my design;

FIG. 2 is a top, front, left perspective view thereof;

FIG. 3 is a bottom plan view thereof;

FIG. 4 is a bottom, rear, right perspective view thereof;

FIG. 5 is a right side elevational view thereof;

FIG. 6 is a front elevational view thereof;

FIG. 7 is a left side elevational view thereof; and

FIG. 8 is a rear elevational view thereof;

FIG. 9 is a top plan view of a second embodiment of a joint for pipes in particular for flexible tubes in accordance with my design;

FIG. 10 is a top, front, left perspective view thereof;

FIG. 11 is a bottom plan view thereof;

FIG. 12 is a bottom, rear, right perspective view thereof;

FIG. 13 is a right side elevational view thereof;

FIG. 14 is a front elevational view thereof;

FIG. 15 is a left side elevational view thereof; and

FIG. 16 is a rear elevational view thereof;

FIG. 17 is a top plan view of a third embodiment of a joint for pipes in particular for flexible tubes in accordance with my design;

FIG. 18 is a top, front, left perspective view thereof;

FIG. 19 is a bottom plan view thereof;

FIG. 20 is a bottom, rear, right perspective view thereof;

FIG. 21 is a right side elevational view thereof;

FIG. 22 is a front elevational view thereof;

FIG. 23 is a left side elevational view thereof; and

FIG. 24 is a rear elevational view thereof;

FIG. 25 is a top plan view of a fourth embodiment of a joint for pipes in particular for flexible tubes in accordance with my design;

FIG. 26 is a top, front, left perspective view thereof;

FIG. 27 is a bottom plan view thereof;

FIG. 28 is a bottom, rear, right perspective view thereof;

FIG. 29 is a right side elevational view thereof;

FIG. 30 is a front elevational view thereof;

FIG. 31 is a left side elevational view thereof; and,

FIG. 32 is a rear elevational view thereof.

The broken lines in FIGS. 9-16 and the blue colored areas

in FIGS. 25-32 represent portions of the joint for pipes in

(Continued)

particular for flexible tubes in which the design is embodied that form no part of the claimed design.
